[57] CLAIM

The ornamental design for a handle, as shown and described.

DESCRIPTION

FIG. 1 is a perspective view taken from the top, front and left side of a handle showing our new design;

FIG. 2 is a left side elevational view thereof, the right side being a mirror image of the left side;

FIG. 3 is a front elevational view thereof, the rear being the same as the front shown;

FIG. 4 is a top plan view thereof;

FIG. 5 is a bottom plan view thereof;

FIG. 6 is a perspective view taken from the top, front and left side of a second embodiment thereof; and

FIG. 7 is a perspective view taken from the top, front and left side of a third embodiment thereof.

The broken line representations of escutcheons in FIGS. 1, 6 and 7 are for purposes of illustration only and form no part of the claimed design.

FIG. 1
